UNITED STATES PATENT OFFICE

ALFRED J. JOHNSON, OF RED WING, MINNESOTA, ASSIGNOR TO PITTSBURGH PLATE GLASS COMPANY, A CORPORATION OF PENNSYLVANIA

LINSEED CAKE DISCHARGER

Application filed January 16, 1929. Serial No. 332,802.

The invention relates to a linseed cake discharger for removing the layers of pressed meal from the cage in which the meal is pressed. The invention has for its principal objects the provision of improved means which will automatically remove the layers of meal from the cage, as they are pushed upward through the cage by the press ram or plunger, and which is so constructed that the tearing of the cloth sheets which separates the layers of meal is avoided. One embodiment of the invention is illustrated in the accompanying drawings, wherein:

Figure 1 is a front elevation of the apparatus. Fig. 2 is a side elevation. And Figs. 3 and 4 are enlarged detail views of the construction of the stripping wheels and their relation to the series of meal cakes or layers.

Referring to the drawings, 1 is the pit in which the lower portion of the apparatus is mounted, and 2, 2 are a pair of beams, which take the weight of the frame and the parts carried thereby. The frame comprises the pair of castings 3 and 4 connected by the four guide rods or posts 5. Supported by the lower casting is the hydraulic cylinder 6, whose plunger 7 extends through the press table 8 guided for vertical movement on the posts 5. The press table is supported from the casting 3 by means of a pair of jacks 9, such table being provided with a drip pan 10 having a pipe 11 leading to the drain 12.

Supported upon the table 8 is a cage 13 carrying the meal cakes or layers 14, from which the oil has been pressed and which must now be removed. These layers are separated by the layers of cloth or felt 15 and are tightly adherent to each other due to the high pressure employed in pressing out the oil. The cage comprises a steel shell of rectangular form open at both ends and when in position on the table 8 is supported against upward movement by the stops 16 resting against the lower side of the casting 4 and secured to the guide posts 5. The cages are brought to position at the side of the apparatus on trucks 17 whose tops lie at the level of the top of the table 8, so that the cages may be easily slid onto the table and removed therefrom.

Extending transversely of the frame at one side thereof (Fig. 2) is a shaft 18 supported in bearings 19, 19 carried by the posts 5, such shaft being driven from the line shaft 20 through the intermediary of the spur wheel 21, the pinion 22 (Fig. 2) on the countershaft 23, the pulley 24 on the shaft 23 and the belt 25 passing around the pulley 24 and the pulley 26 on the line shaft 20.

Keyed to the shaft 18 is a pair of stripping wheels, each comprising a pair of sheet metal discs 27, 27 (Figs. 3 and 4) between which are mounted the series of stripping members or teeth 28, 28, etc. The discs are provided with the hub members 29, 29 keyed to the shaft 18. The members 28 are pivoted on the pins 30, 30, etc. carried by the discs 27, 27 and held against backward movement beyond a certain point by the stop pins 31, 31, etc. also carried by the discs.

The timing of the upward movement of the plunger 7 and the rotation of the shaft 18 is such that, as each layer or cake 14 rises above the top of the cage 13, its edge is engaged by one of the members 28, as indicated in Fig. 4, and such edge is lifted, thus loosening the cake so that the further movement of the stripping wheel pushes it to the left. This operation continues until the entire series of cakes or layers in the cage is removed, at which time the cage is removed onto a waiting truck and another cage is placed in position on the table 8. Further, the timing of the parts is such that the beveled ends of the members 28 engage the edge of the cloth layer 15 for each stripping operation in such manner that the cloth is stripped back without tearing, thus permitting of the repeated use of the cloth members. The effective action of the members 26 is increased by having them pivoted. The members swing down to vertical position and engage the edges of the cakes and their cloth layers before the pins 31 engage the backs of the members, so that in each case an impact effect is secured when the pin strikes the member (already in engagement with the edge of the cake), thus giving a better loosening action than if the members 28 were rigid with respect to the wheel carrying them. The apparatus reduces the

100

hand labor incident to freeing the meal cakes from the cage and from each other, and involves a large saving in time.

What I claim is:

5 In combination in apparatus for discharging meal cakes from the cage in which they are pressed, means for removing the layers of meal as they emerge from the cage comprising a wheel mounted above the cage at
10 one side thereof, a plurality of pivoted teeth carried upon the wheel at equally spaced intervals, stops on the wheel for limiting the movement of the teeth to the rear, and means for rotating the wheel, said wheel being positioned so that its teeth engage the edges of
15 said cakes and separate them from the body of meal cakes in the cage therebeneath.

In testimony whereof, I have hereunto subscribed my name this 7 day of January, 1929.

20 ALFRED J. JOHNSON.
